HAND-HOLE COVER.

1,105,212.

Specification of Letters Patent. Patented July 28, 1914.

Application filed May 24, 1912. Serial No. 699,467.

To all whom it may concern:

Be it known that we, WILLIAM F. SELLERS and HENRY B. BRADFORD, citizens of the United States, residing in Edgemoor, 5 Brandywine Hundred, county of Newcastle, and State of Delaware, have invented a certain new and useful Improvement in Hand-Hole Covers, of which the following is a true and exact description, reference being 10 had to the accompanying drawings, which form a part thereof.

Our invention relates to the construction of hand hole covers or the like, and has for its object primarily to provide a cover of 15 such a character that it can be inserted in the round hole it is to close from the outside and, when turned to closing position will fit in and against a seat in the hole in such manner that even apart from the use 20 of a gasket or packing the cover can not be forced through the hole and will substantially close it.

Further objects of our invention are to 25 improve the means for holding the cover in position, the character of the joint formed by it in the hole it closes and to provide improved means for holding the cover while the nut clamping it in place is being unscrewed.

30 The nature of our improvements will be best understood as described in connection with the drawings in which they are illustrated and in which—

Figure 1 is a view of the hand hole cover 35 and connections taken on the section line 1—1 of Fig. 2. Fig. 2 is a similar view on the line 2—2 of Fig. 1. Fig. 3 is a plan view of the rear face of the cover. Fig. 4 a somewhat exaggerated view of the joint formed 40 by the cover and hand hole seat as shown in Fig. 1, and Fig. 5 a similar view of the joint as shown in Fig. 2.

A is a plate, in the case illustrated a portion of a boiler header, having a round hole 45 formed in it, the outer edges A' of which are at right angles to the surface of the plate as shown, and the inner edge A² of the hole is chamfered to form a more acute angle to the horizontal plane of the hole. At A⁴, 50 A⁴, we have shown walls of the boiler header extending at an angle to its face.

B is the hand hole cover, the peripheral edge C of which is tapered outwardly as 55 shown in the general form of a cone, the tapered edge of the cover being in the upper

or inner portion of greater diameter than the smaller or outer portion of the hole, the relative proportion of the parts being preferably such that the cover will seat itself in the hole with its outer end extending a short 60 distance beyond the outer edge of the hole when no packing or gasket is interposed. In order to enable this cover to be inserted in the hole from outside, we chamfer or bevel off the inner portions of the tapered 65 edges of the cover on opposite sides as shown at D, D, thus reducing the diameter of the cover in one direction to such an extent that it can pass edgewise through the hole, while, when turned to parallelism with the hole, it 70 will fit in it and effectively close it except for very small clearances at the chamfered portions.

E is a finger extending laterally from the inside of the cover and its function is to 75 abut against an obstruction, such as wall A⁴, and prevent the cover from rotating in the hole.

G is a gasket or packing ring of homogeneous metal of a hardness suitable to the 80 pressure to be carried by the joint. It is usually of copper, though iron or steel may be used with advantage when very high pressures are involved, this gasket fits in the seat of the hole and, as clearly shown, forms 85 with the cover a close joint all around the hole. The gasket is of course inserted after the cover has been introduced into the hole and before it is drawn into closing position.

F is the cover holding yoke which we form 90 of dome shape and with its edge F lapping the edge of the hole so as to form an abutment for the outer edges of the gasket G and prevent its being drawn through or too far into the hole when the joint is being 95 made up. The yoke F is formed with a central bolt hole F² through which extends the bolt H secured to the cover in any convenient way and upon the outer end of which screws the nut H' by which the cover is drawn into 100 the hole.

The strains involved are sometimes so great that we have found it most desirable to preserve the dome shape of the yoke and to form no openings in it except the bolt 105 hole, so that should the nut H' become rusted or by other cause fast to the bolt the utility of the finger E on the cover becomes apparent as it prevents the rotation of the cover when the nut H' is being unscrewed. 110

Having now described our invention, what we claim as new and desire to secure by Letters Patent is,

1. A hand hole cover for a round hole in a boiler head or plate having a conical body larger in diameter at its inner end than the hole to be closed and adapted to fit in the hole and against the inner edge which lies inside of the hole, said conical body of the cover being at its larger end cut away or chamfered on opposite sides to reduce its width in one direction to a distance less than the diameter of the hole whereby the cover can be passed edgewise through the hole to be closed and then drawn into the hole until the unchamfered portions of its conical body are arrested by contact with the inside of the hole.
2. A hand hole cover for a round hole in a boiler head or plate comprising a body having a conical outer end portion adapted to enter the hole to be closed, said outer end portion being smaller in diameter at its larger end than said hole and having an inner end portion of larger diameter than said hole but cut away or chamfered at opposite sides to such extent as to permit the cover to be passed edgewise through said hole, said cover having a laterally extending finger projecting from said inner portion and adapted to engage a portion of the boiler lying at one side of said hole, a flexible bushing surrounding said conical end portion and adapted to be wedged between and to seal the joint between said end portion and the peripheral wall of said hole, and a dome shaped clamping yoke having a continuous circular edge lapping over the outer edge of the hole and serving as a stop for said bushing, and means for drawing the cover and yoke together.
3. A hand hole cover for a round hole in a boiler head or plate, comprising a conical body larger in diameter at its large end and smaller in diameter at its small end than the hole to be closed, and having opposite sides of its larger end cut away or chamfered to make the corresponding width of the body less than the diameter of the hole whereby the cover may be passed edgewise through the hole, said cover also having a laterally projecting finger extending from its inner portion and adapted to engage a portion of the boiler lying at one side of said hole.
4. The combination of a boiler head or plate having a round hand hole formed therein with a cover for said hole comprising a body having a conical outer end portion adapted to enter said hole, said outer end portion being smaller in diameter at its larger end than said hole and having an inner end portion of larger diameter than said hole but cut away or chamfered at opposite sides to such extent as to permit the cover to be passed edgewise through said hole, a flexible bushing

surrounding said conical end portion and adapted to be wedged between and to seal the joint between said end portion and the peripheral wall of said hole and a dome shaped clamping yoke having a continuous circular edge lapping over the outer edge of the hole and serving as a stop for said bushing, and means for drawing the cover and yoke together.

5. The combination of a boiler head or plate having a round hand hole formed therein, with a cover for said hole comprising a body having a conical outer end portion adapted to enter said hole, said outer end portion being smaller in diameter at its larger end than said hole and having an inner end portion of larger diameter than said hole but cut away or chamfered at opposite sides to such extent as to permit the cover to be passed edgewise through said hole, said cover having a laterally extending finger projecting from said inner portion and adapted to engage a portion of the boiler lying at one side of said hole, a flexible bushing surrounding said conical end portion and adapted to be wedged between and to seal the joint between said end portion and the peripheral wall of said hole, and a dome shaped clamping yoke having a continuous circular edge lapping over the outer edge of the hole and serving as a stop for said bushing, and means for drawing the cover and yoke together.

6. A boiler head or plate having a round hand hole formed therein and being cut away or chamfered at the inner edge of said hole, in combination with a hand hole cover comprising a body having a conical outer end portion adapted to enter the hole to be closed, said outer end portion being smaller in diameter at its larger end than said hole and having an inner end portion of larger diameter than said hole but cut away or chamfered on opposite sides to such extent as to permit the cover to be passed edgewise through said hole, and a flexible bushing surrounding said conical end portion and adapted to be wedged between and to seal the joint between said end portion and the portion of the peripheral wall of said hole at the outer side of the cut away or chamfered inner edge of said hole.
